Primary Examiner—Elizabeth A Albert*Assistant Examiner*—Karen E Eldridge Powers(74) *Attorney, Agent, or Firm*—Fellers, Snider, Blankenship, Bailey & Tippens, PC(57) **CLAIM**

The ornamental design for a band-shaped cooling pack, as shown and described.

DESCRIPTION

FIG. 1 is a perspective view of a band-shaped cooling pack according to the first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIGS. 1–5 indicate the point of attachment from one segment of the claimed design to the next, as viewed from left to right, and form no part of the claimed design.
